(57) **CLAIM**

The ornamental design for a pivot block for foldable shelving unit, as shown and described.

DESCRIPTION

FIG. 1 is a pivot block for a foldable shelving unit in a perspective view;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view showing the pivot block positioned in a foldable shelving unit.

The even broken lines are included for the purpose of illustrating portions of the pivot block that form no part of the claimed design.

The dash-dot-dash broken lines showing a foldable shelving unit in FIG. 8 represent environmental subject matter.

1 Claim, 8 Drawing Sheets
